UNITED STATES PATENT OFFICE.

JACOB KISSINGER AND EMIL LAU, OF NEW YORK, N. Y.

DESIGN FOR A PRINTER'S GALLEY.

SPECIFICATION forming part of Design No. 25,390, dated April 14, 1896.

Application filed February 19, 1896. Serial No. 579,973. Term of patent 31 years.

To all whom it may concern:

Be it known that we, JACOB KISSINGER and EMIL LAU, citizens of the United States, and residents of New York, in the county of New York and State of New York, have invented and produced a new and original Design for Printers' Galleys, of which the following is a specification, reference being had to the accompanying drawings, forming part thereof.

In the drawings forming part of this specification, Figure 1 is a plan view of our design for a printer's galley, and Fig. 2 a transverse section thereof on the line 2 2, these two views being deemed necessary to fully illustrate our design.

The leading feature of our device for a printer's galley consists in a rectangular casing closed at the bottom and open at the top, the side of said casing being curved or configured longitudinally—that is to say, being provided with an extension H of the base and an outwardly-curved portion C, the top of said portion C being rounded or convex at F, as clearly

shown in the drawings. The contour of the end pieces B and the sides C on their outer surfaces are the same, and the outlines thereof are all regular in form, and when viewed from the top or in plan the bottom portion of the plate A, outside of the sides C and the end B, is not visible, said bottom portion being entirely covered by the flanges K.

Having fully described our new and original design, what we claim, and desire to secure by Letters Patent, is—

The design for a printer's galley, substantially as herein shown and described.

In testimony that we claim the foregoing as our invention we have signed our names, in presence of the subscribing witnesses, this 6th day of February, 1896.

JACOB KISSINGER.
EMIL LAU.
